UNITED STATES PATENT OFFICE

2,446,985

VACUUM CLEANER HAVING A FLOATING NOZZLE

Howard A. Shumaker, Somerville, N. J., assignor to The Singer Manufacturing Company, Elizabeth, N. J., a corporation of New Jersey

Application June 1, 1944, Serial No. 538,304

2 Claims. (Cl. 15—8)

1

This invention relates to a vacuum cleaner. A vacuum cleaner is a heavy object whose weight is such that it has proved to be very difficult to regulate the position of the vacuum nozzle, and the brush or agitator accurately with respect to the surface which is being cleaned. If the nozzle is correctly adjusted for one carpet, it frequently happens that it is not so for other carpets which have a different nap and thickness, because the weight of the machine presses the wheels more or less into the nap of the carpet depending on its texture.

It is an object of the invention to make a vacuum cleaner whose nozzle will be at all times automatically correctly spaced from the working surface, and which is, to a considerable extent, independent of rug texture.

With the above and other objects in view, as will hereinafter appear, the invention comprises the devices, combinations and arrangements of parts hereinafter set forth and illustrated in the accompanying drawings of a preferred embodiment of the invention, from which the several features of the invention and the advantages attained thereby will be readily understood by those skilled in the art.

In the drawings:

Fig. 1 is a plan view of the chassis of the new vacuum cleaner.

Fig. 2 is a plan view of the vacuum nozzle of the new vacuum cleaner showing the brush in dotted lines.

Fig. 3 is a vertical section through the assembled vacuum cleaner.

Fig. 4 is a plan view of the vacuum cleaner with the handle, the motor, and the cover removed.

Fig. 5 is a section on the line 5—5 of Fig. 4.

Fig. 6 is a section on the line 6—6 of Fig. 4.

Fig. 7 is a diagrammatic view partly in vertical section showing the advantageous manner in which this invention functions.

In the drawings like numerals indicate like parts and the description is illustrative, not a limitation.

The chassis 10 of the vacuum cleaner comprises essentially a cast frame 17 affording an air conduit having an intake 11 and an outlet 12, a motor 13 mounted on a plate 14, a fan 15 on the motor shaft to create suction, and a belt pulley 16, also on the motor shaft. The air conduit is composed of a lower chamber 18 and an upper chamber 19 separated by wall 20 having therein an opening 21 which permits free movement of the air. The plate 14 which supports the motor also serves as an upper closure for the upper chamber 19.

2

A rear axle 30 is secured in a seat 33 in the rear end of the chassis and is locked in position by screws 35, carried by a plate 34, which press against a flat portion of the axle. The axle 30 has offset portions 31 on which are journaled rear wheels 32. Drilled legs 36 on the forward part of the chassis casting carry axles 38 on which are journaled a pair of front wheels 37. On the upper portion of the frame 17 are flanges 40 on which a plate 41 is mounted and forms a part of the cover of the conduit; bolt holes 42 in the flanges permit the plate 41 to be secured in a sealed position. A standard 44 is secured to or forms a part of plate 41 and supports a pivoted handle 45. Drilled flanges 50 on the frame 17 form a main motor support to which the motor plate 14 is secured by bolts 51 or the like. The plate 41 has a flange 52 which completes the motor support.

Numerals 60 indicate a pivot stud fixed to the frame 17 by bolts 61. A generally U-shaped floating nozzle member 62 (see Fig. 2) substantially embraces the chassis frame 10 (see Fig. 4) and comprises a nozzle proper and a pair of rearwardly extending spaced arms 69 arranged outside said chassis and having bearings 76 which receive the stud 60; the pivot and mounting being such that the pivot is substantially aligned with the offset axles of the rear wheels. A brush, or a rotary agitator 63 is mounted in the nozzle (in bearings not shown) and is driven by the belt 64 from the pulley 16, which belt transmits power from the motor.

An outlet 65 from the nozzle is connected by flexible conduit 68 to the inlet 11 of the frame conduit. Nozzle-supporting wheels 70 are mounted by axles 71 in the arms 69 and are not connected to wheels 37.

A removable hood or cover 72 is bolted to the chassis at 73 and 77 and extends down over the center portion 66 of the nozzle. The lower edge portions of the side walls of the cover 72 are spaced laterally from the side walls of the frame 17, as shown in Fig. 6. This cover has a removable lens 81 in front of the light bulb 80. Stud screws 74 are mounted in the arms 69, and slotted brackets 75 are mounted in frame member 17, the studs projecting into the slots of elements 75 so that the relative vertical movement possible between the cover and the chassis of the vacuum cleaner is limited. The arms 69 have vertically extending portions located in the space between the lower edge portion of the side walls of the cover 72 and the side walls of the frame 17. These portions of the arms extend upwardly behind the side walls of the cover sufficiently to effect a fin-

ished closure for the frame 17 in all the vertical positions of the nozzle member.

The functioning of the device will be comprehended from the preceding description. In brief, as the cleaner is moved along, the heavy portions, handle, bag, chassis, motor, and cover are borne by the wheels 37 which sink deeply into the rugs and vary their relationship to the surface thereof according to the character of the rug, whereas the light, pivotally mounted nozzle, supported at its front end by wheels 70, maintains its proper distance therefrom with substantial uniformity.

The operation of the invention is illustrated in Fig. 7, wherein is shown how the wheels 32 and 37 sink into a carpet or rug having a soft nap under the weight of the heavy parts of the machine, while the wheels 70 which carry the much lighter weight of the brush and nozzle ride on the surface of the carpet and maintain the proper relation of the nozzle thereto.

Another advantage is that the wear on carpeting caused by the brush or agitator is reduced because the nozzle and brush are not forced into too close contact with the rug by the weight of the chassis.

The nozzle is shown in Figs. 2 and 3 to be partly within the cover, but the cover could be omitted without impairing the function of the machine.

As many apparently widely different embodiments of this invention may be made without departing from the spirit and scope thereof, it is to be understood that I do not limit myself to the specific embodiments thereof except as defined in the appended claims.

Having thus set forth the nature of the invention, what I claim herein is:

1. A vacuum cleaner having a chassis comprising a frame supported by front and rear wheels, an air conduit constructed therein having an intake toward the front and an outlet toward the rear thereof, the intake portion of said air conduit extending below the main forward portion of said cleaner frame, a motor mounted on the frame, a fan in the conduit operated by the motor to impel air through the conduit toward the outlet, a vacuum nozzle member comprising a nozzle proper and a pair of horizontally disposed and rearwardly extending spaced arms substantially embracing said frame and pivoted to the rear portion thereof in substantial axial alignment with said rear wheels, auxiliary wheels supporting said nozzle, and positioned in substantial axial alignment with said front wheels, a lost-motion connection between said frame and nozzle member, forwardly of said pivot, to limit the relative movement between said frame and member, a rotary brush in said nozzle, means to drive the brush from the motor, and flexible conduit means connecting a portion of the nozzle and said intake for relative motion.

2. A vacuum cleaner having a chassis comprising a frame and an appearance housing carried by said frame, an air conduit constructed in said frame and having an intake opening at the front and an outlet opening at the rear of said frame, a portion of said air conduit including said intake extending below the main portion of said frame and extending toward the forward portion of said cleaner, a motor mounted on said frame, a fan in said conduit and operated by said motor to impel air through said conduit toward said outlet opening, a pair of front main wheels rotatably carried on the front part of said frame, a pair of rear main wheels rotatably carried on the rear part of said frame, said front and rear main wheels supporting said frame, appearance housing, air conduit, motor and fan, a substantially U-shaped floating nozzle member comprising a nozzle proper and a pair of horizontally disposed and rearwardly extending arms embracing said frame and said intake portion of said air conduit and pivotally connected to the rear portion thereof in substantial alignment with the rotation axis of the rear wheels, a pair of spaced auxiliary wheels supporting the front end of said nozzle and having their rotation axis in substantial alignment with the rotation axis of said front main wheels, means positioned forwardly of the pivotal axis of said arms for limiting the relative movement between said nozzle member and said frame, a rotary brush in said nozzle proper, means to drive said brush from said motor, and flexible conduit means connecting a portion of said nozzle proper between said arms to said intake opening for relative motion, said auxiliary wheels and said rear main wheels wholly supporting said nozzle member and said brush.

HOWARD A. SHUMAKER.
